CLAIM

The ornamental design for a display screen or portion thereof with animated graphical user interface, as shown and described.

DESCRIPTION

The patent or application file contains at least one drawing executed in color. Copies of this patent or patent application publication with color drawing(s) will be provided by the Office upon request and payment of the necessary fee.

1. Display screen or portion thereof with animated graphical user interface

1.1 : First image

1.2 : Second image

1.3 : Third image

1.4 : Fourth image

1.5 : Fifth image

1.6 : Sixth image

1.7 : Reference view 1

1.8 : Reference view 2

1.9 : Reference view 3

1.10 : Reference view 4

1.11 : Reference view 5

1.12 : Reference view 6

The appearance of the animated graphical user interfaces sequentially transitions between the images, the process or period between which one image transitions to another forms no part of the claimed design; the broken lines showing of display screen or portion thereof are for the purpose of illustrating environment and form no part of the claimed design; the reproductions 1.7-1.12 are reference view showing the state in use of the claimed design and form no part of the claimed design.
